UNITED STATES PATENT OFFICE.

EDWIN T. GREENFIELD, OF KIAMESHA, NEW YORK.

ART OF TREATING METAL AND OTHER TUBES OR RODS.

947,439.

Specification of Letters Patent. Patented Jan. 25, 1910.

Original application filed March 25, 1909, Serial No. 485,735. Divided and this application filed July 17, 1909. Serial No. 508,133.

To all whom it may concern:

Be it known that I, EDWIN T. GREENFIELD, a citizen of the United States, and resident of Kiamesha, county of Sullivan, and State of New York, have made a new and useful Invention in the Art of Treating Metal and other Tubes or Rods, of which the following is a specification:

My invention is directed particularly to a novel method of treating metal tubes or rods with liquid coatings and it has for its objects, first, to effect such coating automatically and with great speed; second, to effect the interior coating of tubes of this nature in such manner as to give a smooth lining thereto which will afford little or no skin friction or resistance to the flow of gas, water, or other liquids; third, to provide novel means for effectually drying and seating the treating liquid as applied by my novel method to tubes or rods.

For a full and clear understanding of my invention, such as will enable others skilled in the art to practice the method hereinafter described and claimed, reference is had to the accompanying drawings which illustrate my novel mechanism by which such method is effected and in which Sheets 1, 2 and 3 should be placed end to end with Sheet 1 upon the left of Sheet 2 and Sheet 2 upon the left of Sheet 3.

Figure 1 of the drawings represents a side elevational view of that portion of the apparatus in which the tubes or rods to be treated are first heated to the desired temperature and then fed forward to the treating bath, one end of the heater being shown in broken sectional view for the purpose of illustrating the interior structure thereof, the dotted lines on the extreme right illustrating that portion of the apparatus through which the tubes or rods are successively fed to the treating bath. Fig. 2 is a plan view of Fig. 1 as seen looking thereat from the top toward the bottom of the drawing. Fig. 3 is a transverse sectional view taken through Fig. 2 on the line X—X and as seen looking thereat from left to right in the direction of the arrows, the top or inclosing door being shown in this figure in closed position in full lines and in open position in dotted lines. Fig. 4 is a part side elevational, part sectional view (on the line Z—Z Figs. 5 and 7) of that portion of the treating bath by which the coating is effected and the liquid coating

medium heated; the hinged top of the treating chamber being shown in open position, one of the tubes being treated and fed forward and in two different positions, as shown in full lines and dotted lines; a portion of the mechanism by which the tubes are successively wiped, both exteriorly and interiorly, and fed forward after treatment, being shown on the right hand end of said figure. Fig. 5 is a part plan, part longitudinal sectional view of the mechanism shown in Fig. 4, the sectional view being taken through the treating chamber alone. Fig. 6 is a further sectional view on the line Z—Z Fig. 7, illustrating the continuation of that portion of the wiping and feeding mechanism shown on the right of Fig. 4. Fig. 8 is a plan view of Fig. 6. Fig. 8 is a part horizontal sectional and part plan view on an enlarged scale of that portion of the apparatus which effects the interior wiping of the tubes and the interconnected mechanism by which the same are successively fed forward after treatment; and Fig. 9 is a transverse sectional view taken through Fig. 8 on the line Y—Y and as seen looking thereat from left to right in the direction of the arrows.

My invention is particularly designed to effect a treatment of metal tubes by subjecting the same to a heated bath of some liquid which will effectually coat the same both exteriorly and interiorly, and with the greatest possible speed, and will subsequently wipe and polish the same; the entire mechanism being preferably automatic in its operation and so arranged that such tubes are first subjected to sufficient heat to seat or set the coating as they are advanced through a treating bath, which bath is in turn subjected to heat from a furnace or the like. The tubes are then automatically advanced in sequence and successively wiped, both exteriorly and interiorly while still hot, the exterior wiping being effected by means in the nature of a stationary wiper of proper softness and flexibility, the interior wiping being subsequently effected through the agency of what I term a "floating wiper" which is so devised that as the tubes are successively fed forward the interior is given a polished surface which will be practically as frictionless as that of porcelain lined tubes.

Prior to my invention it has been customary to treat metal tubes, such as iron or

the like, to so-called galvanizing coatings, by immersing such tubes in a bath of molten zinc, tin, and like liquids, and then removing the same from the bath and successively wiping them first on the exterior surface and subsequently, interiorly. Such methods are slow and unsatisfactory and the tubes cool too quickly after the bath to obtain the best results. My novel method of treating metal tubes in the manner hereinafter described gives marked improved results over such old methods, in that I am enabled to avoid practically all loss of heat units from the time that the tube enters, passes through, and leaves the bath until it is effectually wiped, both exteriorly and interiorly.

An important step in my novel method is that of first heating the tubes before they are immersed in the heated liquid bath. I have ascertained that in the practice of well known methods heretofore used in galvanizing or treating metal tubes in a heated liquid bath, it usually requires about three minutes to properly heat the tubes before the liquid galvanizing agent takes effect, so that when tubes of this nature are sufficiently heated before they enter the bath they are caused to be galvanized or treated during the time that they are passing therethrough and without being stopped, thus permitting of a continuous or successive feed of such tubes through the bath.

Referring now to the drawings in detail, in all of which like numerals of reference represent like parts, and first to Figs. 1 to 3 (Sheet 1) 1 represents a frame or structure embodying a series of inclined members supported by vertical standards, as shown, and carrying in turn a floor 2 upon which is supported a metal heating chamber 3 provided with a pivoted door 4 at its top. This chamber is of the desired length and capacity to subject the tubes 5 to be treated to the usual preliminary necessary heat before advancing the same to the treating bath. 6 represents a tube connected with a source of fuel supply as gas, and 7, 7, are two branches entering at the bottom of the heating chamber 3 and extending the entire length thereof. 8, 8 are vertically disposed tubes extending therefrom upward within the inner walls of the chamber, there being four such sets of tubes which are provided with gas-jets or openings 9, 9, 9, 10, 10, 10 represent a series of rolls utilized generally throughout the apparatus for reducing the friction in the movement of the tubes 5 as they are successively advanced, it being apparent that the chamber 3 is open longitudinally at its bottom so that these tubes while being heated rest the first one upon the friction rolls and each successive tube upon the top of the other.

Referring now to Figs. 4 and 5 (Sheet 2) and in connection therewith to that portion

of Fig. 1 illustrated in dotted lines on the right thereof, 12 represents the brick work of a furnace of proper dimensions and strength to support upon its top a liquid containing treating chamber 13, said chamber being preferably of box form and of metal or such other material as will withstand the relatively great heat of the furnace. 14 represents the pivoted lid or cover of such chamber, shown in this figure as in open position for permitting of the examination of the treating bath. 15 represents a throat at one end of the treating chamber for aiding in the movement of the tubes for properly focusing the ends thereof as they are successively advanced through the chamber and to the wiping mechanism exterior thereto. 16, 16 represent the doors of the furnace and 17 the chimney for conveying away the products of combustion. This heating chamber may be heated by steam, gas, or any other source of heat, having sufficient capacity to heat the liquid treating agent to the desired temperature. 18 is a cone-shaped throat for guiding the tubes into the treating bath and 19 represents a similar throat located near the center thereof. 20, 20 represent, wherever used throughout the drawings, pairs of grooved feeding rolls located in alinement with each other and in direct alinement with all of the tubes 5, as they are being fed from the primary heating chamber 3, Fig. 1, there being shown six such pairs of rolls interconnected by gearing and sprocket wheels and chains, as clearly illustrated in Figs. 5 and 7, that pair on the left of Fig. 5 being operatively connected with a shaft carrying a pulley 21 which is connected in turn by a belt 22 with a driving source of energy, as an electric motor 23. It will also be understood that each pair of feeding rolls is provided with the necessary yielding adjusting means for varying the feed pressure between the rolls and tubes 5, so as to give the desired tractive effect upon the tubes, such adjustable means being shown on one pair of the rolls at the extreme left of Figs. 4 and 5. 24 shown at the extreme right hand end of Fig. 4 represents a flexible wiper having the same interior conformation as the exterior conformation of the tube or rod to be wiped; such wiper being secured in front of the outlet of the throat 15 by a tubular retaining collar 25 detachable from the chamber 13 through the agency of screws or bolts.

Referring now to Figs. 6 and 7 (Sheet 3) and to the extreme right hand portion of Figs. 4 and 5 (Sheet 2) 26 represents a floor similar in a general way to the floor 2 and secured to the extreme right hand end of the treating chamber 13, so that its upper surface is inclined as shown and practically in vertical alinement with the outlet of the throat 15, said floor being sustained at its

outer end by standards, as shown in Fig. 6. 27 is an extension of this floor in the nature of a chute preferably curvilinear in cross section and having an inclination the reverse 5 of that of the floor 26. 28 represents an additional floor secured at one end directly to the top of the brick work of the furnace 12 and at the other at a point near the outer end of the chute 27. The material of this 10 floor 26, 27 and side walls, not shown but secured thereto, is preferably of iron for the purpose of constituting a heat retaining chamber adapted to be supplied with heat from the furnace 12 through a pipe 11, the 15 function of this chamber being to give additional heat for the purpose of further drying or curing the tubes or rods as they are forced forward.

Referring to Figs. 8 and 9 (Sheet 4) in connection with the description already had as to Figs. 4, 5, 6 and 7 I will describe the structural parts of the apparatus by which the tubes or rods are successively fed forward as they are treated and successively wiped or polished interiorly, the structural features of this apparatus being illustrated in detail in these figures of the drawings. 29, 29, 29, 29 represent two pairs of vertical standards secured directly to the floor 26, the 30 distance between these two pairs of standards being somewhat greater than the lengths of the individual tubes or rods 5 to be treated. To these pairs of standards are slidably secured two pairs of internally corrugated clutching or holding devices 30, 30, 35 adapted to be forced forward toward each other by strong spiral springs 31, 31, 31, 31, which springs are made adjustable through the agency of screwthreaded adjusting devices 32, 32, 32, 32. 33 represents the supporting rod of the floating wiper, one end of which rod is enlarged and corrugated as shown and provided with a cone-shaped guiding point or head, the other end thereof being screw-threaded and adapted to be secured directly to an entirely similar corrugated and cone-shaped end, said corrugated and cone-shaped ends being both represented by the numeral 36. These corrugations 40 respond in turn with the like corrugations in the curvilinear opposite faces of the pairs of holding devices 30. To the opposite ends of said holding devices are secured pairs of guide-rolls 37, 37, there being two such pairs 45 at each end of the floating wiper. 34, 34 represent respectively sectional tubular sleeves and 35, 35 wipers of soft or flexible material adapted to be threaded upon the rod 33 between the respective tubular sections 34 and having the conformation or shape shown. These wipers and the wiper 24, Fig. 4, may be made of such material as asbestos, or other cloth; or, in fact of any yielding material which will give the desired interior surface polish or finish to the

tubes being treated. This rod 33 and attached parts are combined in the manner clearly illustrated in the drawings and secured in place normally with the curvilinear corrugated faces of the holding devices 30, 70 firmly but yieldingly gripping or clamping the same in the manner shown on the left of Fig. 8, both ends of such rod being normally held as shown on the left when no tube is being fed forward. As illustrated in Fig. 8, 75 the incoming end of a tube 5 which has just been treated in the bath, is shown as approaching the cone-shaped end 36 of the floating wiper and the retiring end of a preceding tube is shown on the right as having 80 been previously wiped exteriorly and interiorly and as it is being advanced onward toward the chute 27 through the feeding rolls 20.

The manner of treating tubes with my 85 novel invention will now be described, it being understood that a proper quantity of the liquid bath with which the tubes are to be treated has been placed in the treating chamber, as for instance, a liquid embracing the usual materials constituting a bath for the so-called galvanizing of iron tubes, and that the same is kept heated to the desired temperature by heat from the furnace 12. The desired number of tubes 5 having been 90 previously pickled by treatment with a diluted acid of the proper character to remove the scales, oils, and other extraneous substances, the same are placed in the heating chamber 3 and the gas having been ignited 95 they—the tubes—are heated to the proper temperature to effect treatment in the bath. The motor 23 (Fig. 5) is then set in motion so as to effect the feed of the tubes through the agency of the interconnected sprocket 100 chains and gear-wheels, in the direction shown by the arrows. The lower tube 5 is then, either manually or by driving rolls like those numbered 20, advanced over the rolls 10 until the outer right hand end thereof enters the first pair of feeding rolls on the left of Fig. 4. It is then immediately advanced in this heated condition into the heated bath in the treating chamber 13 and is again fed forward through the cone-shaped throat 19 to the second set of feeding rolls 20, which rolls, it will be noted, are sufficiently far in advance at the right hand end of the chamber to permit the rear end 110 of the tube to drop by its own weight, when it is fully within said chamber, in the direction of the arrow, and into the position shown in dotted lines. It is aided further in this movement, in the event of its failure to drop by its own weight, by the inclination 115 of the throat 15. As the tube advances and passes outward under the under side of the guide-rolls 10, 10 in the bath it is wiped exteriorly by the wiper 24, and the cone-shaped end 36 of the rod 33 enters the inner end 120 125 130

thereof, while the outer surface passes between the ends of the guide-rolls 37 forcing the holding devices 30, 30 apart from each other to an extent equal to the diameter of 5 the outer wall, thus liberating this end of the rod 33 and permitting the tube to be advanced through the first pair of feeding rolls 20 on the right of the heating chamber. As the tube is further advanced, therefore, 10 by this pair of feeding rolls and is released from the last pair of such rolls within the chamber, its inner surface is successively wiped or polished by the series of wipers 35, 35, and these wipers being of proper material 15 and individually so constructed as to give the best possible polish to the inner surface of the tube, will act in accordance with such conditions and completely wipe or polish the interior thereof, it being understood 20 that the holding devices 30, 30 on the right for the rod 33 and its interconnected parts will be held in gripping mechanical connection with the corrugations on the end 36, so that during the time that the holding 25 devices 30, 30 on the extreme left hand end are held apart and the wiping is being effected, said rod will be mechanically held at its right hand end, and that after the tube is advanced over the wipers and the left hand 30 end thereof released from the holding devices 30, 30 on the left, the right hand end of said tube will separate the holding devices 30, 30 on the extreme right in the same manner as it separated the like devices on 35 the extreme left. In the meantime the holding devices on the extreme left will have been released as the left hand end of the tube passes from between them, so that now the floating rod and its attached parts will be 40 held by the holding devices on the extreme left. It is thus apparent that each pair of holding devices successively holds this floating rod and accompanying parts as the tubes are being advanced. As the rod 5 is finally 45 advanced under the pair of feeding rolls 20 at the extreme right of Fig. 8 and is again seized by the next pair of such rolls, the last pair of holding devices 30, 30 will assume the holding position shown by the pair on 50 the extreme left, thus holding said floating rod and parts. Finally such tube passes outward in the direction of the arrows shown in Fig. 6 over the heating chamber which is heated from the furnace through the pipe 11 55 and in dried condition is released from the last pair of rolls on the extreme right of Fig. 6 and permitted to slide down the chute 27 over the rolls 10, 10 in its completed treated condition. 60 If the apparatus described and shown be used for treating and wiping rods, obviously the interior wiping device would be dispensed with, the feed rolls, however, shown in connection with Figs. 8 and 9, being re- 65 tained for the purpose of advancing the rods

until finally delivered over that part of the apparatus shown in Fig. 6.

I do not limit my invention to the details of construction illustrated in the accompanying drawings for practicing the method of treatment hereinbefore described, such invention being directed generically to a method of treatment, regardless of the structural nature of the parts by which this result is attained. Nor do I limit myself to the treatment of tubes, as obviously solid rods may be treated in this manner, or hollow tubes may be simply treated externally and wiped in the manner described without applying the interior wiping treatment where it is desired to construct either tubes or rods having a polished exterior surface, it being apparent that in this instance the interior wiping mechanism illustrated in Figs. 8 and 9 of the drawings may be dispensed with, and in which event the exterior heating chamber would be of especial utility; as, for instance, in cases where tubes or rods are being treated with various types of bronze paints or liquid surfacing agents to which it is desired to give a finished appearance, my invention being directed generically to a method of treating either tubes or rods in the manner described and for uses generally in the arts, the same having especial utility in treating tubes or rods with lacquering liquids; or, in all such uses where tubes or rods are treated with surfacing coatings.

I am aware that it is broadly old in the art of galvanizing iron or analogous wire to subject it to a bath of molten metal and draw the same therefrom through one or more masses of flexible wiping material, such as cotton waste, asbestos, and the like, thus giving to the wire a polished galvanized coating, and I make no claim hereinafter broad enough to include such methods, my invention being directed to the coating of rigid metallic tubes, either exteriorly or interiorly, or both, and the wiping of such tubes exteriorly, or both exteriorly and interiorly, as they are forced forward from the bath.

No claim is made hereinafter to the mechanism for treating metal tubes or rods with liquid coatings, as the same constitutes the subject matter of an application filed by me in the U. S. Patent Office on the 25th day of March, 1909, bearing Serial No. 485,735, and of which the present application is a division.

Having thus described my invention what I claim and desire to secure by Letters Patent of the United States is—

1. The described method of treating a tube or rod so as to give to the same a smooth or polished exterior surface, consisting in first heating it, then subjecting it to a heated liquid bath in the nature of a polishing agent, and finally wiping the same as it is withdrawn from the bath in heated condition.

2. The described method of treating a tube so as to give to the same a smooth or polished interior surface, consisting in first subjecting the tube to a heated liquid bath in the nature of a polishing agent, and then heating and wiping the interior surface until the desired degree of smoothness is effected.

3. The described method of treating a tube so as to give to the same a smooth or relatively frictionless interior, consisting in first heating it, then subjecting it to a heated bath of a liquid surfacing agent, and finally wiping the same interiorly as it is withdrawn from the bath.

15 4. The described method of treating a tube so as to give to the exterior and interior surfaces thereof the desired qualities as to appearance and smoothness respectively, consisting in first subjecting the same to a heated liquid agent, then rubbing both surfaces as the tube is withdrawn from the bath.

5. The described method of treating a tube so as to give to the exterior and interior surfaces thereof the desired qualities as to appearance and smoothness respectively, con-

sisting in first heating the same, then subjecting it to a bath of a heated liquid agent, then rubbing both surfaces as it is withdrawn from the bath and while subjected to further heat.

6. The described method of giving to a metallic tube a smooth interior surface, consisting in subjecting it to a bath of heated liquid coating agent, then removing it from the bath, and finally wiping its interior surface while still in heated condition.

7. The described method of treating a tube so as to give to it a smooth protecting coating, consisting in subjecting it to a heated bath of a galvanizing agent, then automatically lifting and removing it from the bath, and finally wiping it both exteriorly and interiorly while it is still in heated condition.

In testimony whereof I have signed my name to this specification in the presence of 45 two subscribing witnesses.

EDWIN T. GREENFIELD.
